TOY VEHICLE

Larry R. Wood, Redondo Beach, Calif., assignor to Mattel, Inc., Hawthorne, Calif.

Filed Apr. 19, 1972, Ser. No. 245,686

Term of patent 14 years

Int. Cl. D21—01

U.S. Cl. D34—15 AJ

FIG. 1

FIG. 2

FIG. 3

FIG. 4

FIG. 5

FIG. 6

FIG. 1 is a left side elevational view of the toy vehicle showing my new design;

FIG. 2 is a top plan view thereof;

FIG. 3 is a front elevational view thereof;

FIG. 4 is a right side elevational view thereof; the left side being substantially a mirror image thereto;

FIG. 5 is a bottom plan view thereof; and

FIG. 6 is a rear elevational view thereof.

I claim:

The ornamental design for a toy vehicle, as shown and described.
